ABSTRACT OF THE DISCLOSURE

The conversion of contaminated hydrocarbonaceous material commonly referred to in the art as "black oil." Charge stock is initially admixed with liquid product effluent, the mixture being separated to provide a heavy fraction boiling above the gasoline boiling range. This heavy fraction is introduced into a sectioned, sub-atmospheric flash zone to provide a synthetic crude to be converted into lower boiling hydrocarbon products. The flash zone is sectioned in its lower portion to provide two separate flash chambers having a common upper portion for distillation.

APPLICABILITY OF INVENTION

The invention described herein is adaptable to a process for the conversion of petroleum crude oil, and heavier fractions derived therefrom, into lower boiling hydrocarbon products. More specifically, the present invention is directed toward a process for converting atmospheric tower bottoms products, vacuum tower bottoms products (vacuum residuum), crude oil residuum, topped crude oils, crude oils extracted from tar sands, etc., all of which are commonly referred to as "black oils." In particular, the process herein defined affords the maximum production of gasoline boiling range hydrocarbons from such material.

Petroleum crude oils, particularly the heavy oils extracted from tar sands, topped or reduced crudes, and vacuum residuum, etc. contain high molecular weight sulfurous compounds in exceedingly large quantities. In addition, such crude, or black oils contain excessive quantities of nitrogenous compounds, high molecular weight organo-metallic complexes comprising principally nickel and vanadium, and asphaltic material. The high molecular weight asphaltic material is generally found to be complexed with sulfur and, to a certain extent, with the organometallic contaminants. Currently, an abundant supply of such hydrocarbonaceous material exists, most of which has a gravity less than 25.0° API, and a significant quantity of which has a gravity less than 10.0° API. This material is generally further characterized by a boiling range indicating that 10% by volume, and very often more, boils above a temperature of about 1050° F. The utilization of these high molecular weight black oils, as a source of more valuable liquid hydrocarbon products, is precluded by present-day refining techniques, due especially to the exceedingly high sulfur and asphaltic concentrations. The conversion of a significant proportion of the charge stock into distillable hydrocarbons—i.e., those boiling below about 1150° F.—has hitherto been totally nonfeasible from an economic standpoint. Yet, the abundant supply virtually demands such conversion, especially as a means for satisfying the ever-increasing need for greater volumes of the lower boiling distillables, particularly those within the gasoline boiling range.

The process of the present invention is directed toward the catalytic conversion of black oils into distillable hydrocarbons boiling in the gasoline boiling range in volumetric yields of 100.0% or more, based upon the

2

volume of charge stock. Specific examples of the black oils, illustrative of those to which the present scheme is applicable, include a vacuum tower bottoms product having a gravity of 7.1° API at 60° F., containing 4.05% by weight of sulfur and 23.7% by weight of asphaltics; a "topped" Middle-East Kuwait crude oil, having a gravity of 11.0° API at 60° F., containing 10.1% by weight of asphaltenes and 5.20% by weight of sulfur; and, a vacuum residuum having a gravity of 8.8° API at 60° F., containing 3.0% by weight of sulfur and 4300 p.p.m. of nitrogen and having a 20.0% volumetric distillation point of 1055° F. The present invention affords the conversion of the majority of such material into gasoline boiling range distillable hydrocarbons, heretofore having been considered virtually impossible to achieve on an economically feasible basis. The principal difficulty resides in the lack of a suitable technique for producing lower boiling products, substantially free from sulfur and other contaminants, in the presence of the asphaltic material. This asphaltic material consists primarily of high molecular weight, nondistillable coke precursors, insoluble in light hydrocarbons such as pentane or heptane, which are often found to be complexed with nitrogen, metals and sulfur. Generally, the asphaltic material is dispersed within the crude oil, and, when subjected to elevated temperatures, has the tendency to flocculate and polymerize whereby the conversion thereof to more valuable oil-soluble products becomes extremely difficult. Thus, the heavy bottoms from a crude oil vacuum distillation column (vacuum residuum), indicates a Conradson carbon residue factor of, for instance, 16.0% by weight. Such a material is useful only as road asphalt, or as an extremely low grade fuel when cutback with distillate hydrocarbons such as kerosene, light gas oil, etc.

PRIOR ART

Heretofore, in the field of catalytic processing of such hydrocarbonaceous material, two principal approaches have been advanced: liquid-phase hydrogenation and vapor-phase hydrocracking. In the former type of process, liquid phase oil is passed upwardly, in admixture with hydrogen, into a fixed-fluidized catalyst bed, or slurry of sub-divided catalyst. Although perhaps effective in converting at least a portion of the oil-soluble organometallic complexes, this type process is relatively ineffective with respect to asphaltics which are dispersed within the charge. Furthermore, since the hydrogenation reaction zone is generally maintained at an elevated temperature of at least about 500° (932° F.), the retention of unconverted asphaltics, suspended in a free liquid phase oil for an extended period of time, results in additional flocculation and agglomeration, making conversion thereof substantially more difficult. This type process requires an attendant high capacity regeneration system in order to implement the process on a continuous basis. Briefly, the present invention encompasses a method whereby the asphaltic material is maintained in a dispersed state within a liquid phase rich in hydrogen. This material comes into intimate contact with a catalyst capable of effecting reaction between the hydrogen and asphaltic material; the liquid phase is itself dispersed in a hydrogen-rich gas phase so that the dissolved hydrogen is continually replenished. The two-fold dispersion and rapid, intimate contacting with the catalytic surface overcome the difficulties encountered in previous processes whereby excessive residence times and depletion of localized hydrogen supply permit agglomeration of asphaltics and other high molecular weight species. Such agglomerates are even less available to hydrogen and are not, therefore, susceptible to catalytic reaction. They eventually form coke which becomes deposited on the catalyst, thereby further reducing catalytic activity within the system.

OBJECTS AND EMBODIMENTS

The principal object of the present invention is to provide an economically feasible catalytic process for converting black oils into distillable hydrocarbons of lower molecular weight and boiling range. A corollary objective is to maximize the production of gasoline boiling hydrocarbons from black oils boiling above the normal gasoline boiling range.

Another object is to convert sulfur-contaminated heavy hydrocarbon charge stocks, a significant proportion of which boils in the range above a temperature of 1050° F., into lower-boiling distillable hydrocarbon products of significantly reduced sulfur concentration.

Another object of my invention is to provide a process for the conversion of black oils having a gravity, °API, less than about 25.0, and especially to produce distillable hydrocarbons from charge stocks, or portions thereof, having an °API gravity less than about 10.0.

Still another object is to provide a multiple-stage catalytic process for the conversion of black oils into gasoline boiling range hydrocarbons in volumetric yields greater than 100.0%, based upon the fresh charge stock.

Therefore, in a broad embodiment, the present invention involves a process for the conversion of an asphaltene-containing, sulfurous hydrocarbon charge stock into lower-boiling hydrocarbon products, which process comprises the steps of: (a) admixing said charge stock with a normally liquid hydrocracked product effluent and separating the resulting mixture to provide an asphaltene-containing heavy fraction having an initial boiling point above about 350° F.; (b) introducing said fraction into one side of a subatmospheric, sectioned flash chamber and withdrawing a first liquid phase from said side; (c) reacting said first liquid phase with hydrogen at a temperature above about 700° F. and a pressure greater than about 1000 p.s.i.g. in a first catalytic reaction zone, and separating the resulting reaction zone effluent in a first separation zone, at substantially the same pressure and at a temperature above about 700° F., to provide a second liquid phase and a first vapor phase; (d) introducing at least a portion of said second liquid phase into a second side of said subatmospheric sectioned flash chamber, removing an asphaltene-containing residuum fraction from said second side and a second vapor phase from an upper, nonsectioned portion of said flash chamber; (e) separating said first vapor phase in a second separation zone, at a temperature of from 60° F. to about 140° F. and a pressure substantially the same as said first separation zone, to provide a third liquid phase and a hydrogen-rich third vapor phase, and recycling at least a portion of the latter to combine with said first liquid phase; (f) combining said third liquid phase with said second vapor phase and reacting the resulting mixture with hydrogen in a second catalytic reaction zone at conditions selected to convert nitrogenous and sulfurous compounds into hydrogen sulfide, ammonia and hydrocarbons, and to produce lower molecular weight normally liquid hydrocarbons; (g) reacting at least a portion of the resulting second reaction zone effluent in a third catalytic reaction zone at hydrocracking conditions and in contact with a hydrocracking catalytic composite; (h) separating the resulting third reaction zone effluent, at a temperature of from about 60° F. to about 150° F., in a third separation zone to provide a hydrogen-rich fourth vapor phase and a fourth normally liquid hydrocarbon phase; and, (i) combining said fourth liquid phase with said charge stock and separating the resulting mixture as aforesaid.

Other embodiments of my invention reside in particular operating conditions and the use of specific internal recycle streams. The latter include recycle of the hydrogen-rich third gaseous phase to combine with the fresh charge stock prior to reacting the same in the conversion zone. In the specific example which follows, this gaseous phase constitutes more than about 80.0% hydrogen. At least a portion of the second liquid phase is diverted and

combined with the first liquid phase and hydrogen, serving in part as a solvent stream to keep the native asphaltics dispersed and available to both hydrogen and catalyst in the reaction zone. In a preferred embodiment, a second portion of the second liquid phase is cooled and recycled to the inlet of the first separation zone to serve as a quench of the reaction zone effluent such that the temperature in said first separation zone is maintained below a maximum level of 760° F. Thus, the first separation zone is controlled at a temperature within the range of from about 700° F. to about 760° F. A lower temperature permits ammonium salts, resulting from the conversion of nitrogenous compounds, to fall into the liquid phase, whereas a higher temperature permits the heavier hydrocarbons to be carried over with the vapor phase. The quantity of this second liquid phase being recycled to combine with the charge to the first reaction zone is sufficient to maintain a combined feed ratio in the range of 1:5 to about 3:5.

The hydrogen-rich fourth vapor phase is recycled to combine with the normally liquid hydrocarbon charge to the second catalytic reaction zone. In a particularly preferred embodiment, the mixture of fresh charge stock and the hydrocracked product effluent, or the fourth liquid phase, is initially separated to provide a heavy fraction and a middle-distillate boiling range fraction—i.e., having an initial boiling point of about 400° F. and an end boiling point of about 650° F. This middle-distillate fraction is then introduced, as part of the normally liquid hydrocarbon charge, into the second catalytic reaction zone. Other objects and embodiments will become apparent from the following further description of the present process, particularly the description of the illustrated embodiment in the accompanying drawing.

SUMMARY OF INVENTION

Since the hot heavy oil from the conversion zone can give rise to serious emulsification problems, the hot separator (first separation zone) is employed to separate the heavy oil as a liquid phase from a vapor phase containing lighter hydrocarbons, hydrogen and water. This hot separator is maintained at essentially the same pressure as the reaction zone and at essentially the temperature of the reaction zone effluent; as above set forth, in a preferred embodiment, the temperature is controlled in the range of about 700° F. to about 760° F.

A hot flash zone functions at a significantly reduced pressure of from subatmospheric to about 100 p.s.i.g., and may comprise a low-pressure flash zone—i.e. about 60 p.s.i.g.—in combination with a vacuum column maintained at about 50–60 mm. of Hg absolute. The hot flash system serves to eliminate further the difficulties stemming from emulsification problems by providing a residuum fraction containing the unconverted asphaltics and a significant amount of those sulfurous compounds of exceedingly high molecular weight which are not converted in the first catalytic reaction zone. In addition, subsequent separations and product recovery facilities are greatly simplified. As hereinafter described in more detail, the hot flash zone is sectioned, in the lower portion thereof, by means of an imperforate plate. There is provided, thereby, two individually distinct flash zones, into one of which the heavy fraction, resulting from the initial separation of the mixture of charge stock and hydrocracked product effluent, is introduced. Some of the mixture will flash into the upper distillation portion of the flash zone, which portion is commonly shared, or in open communication with the second side of the flash zone, into which the liquid phase from the hot separator is introduced.

Before describing the process with reference to the accompanying drawing, several definitions are believed necessary in order that a clear understanding of the present invention be afforded. In the present specification and the appended claims, the phrase "pressure substantially the same as," is intended to connote that pressure under which

a succeeding vessel is maintained, allowing only for the pressure drop experienced as a result of the flow of fluids through the system. For example, where the conversion zone pressure, measured at the inlet thereof is 2650 p.s.i.g., the hot separator will function at about 2530 p.s.i.g. Similarly, unless otherwise specified, the phrase "temperature substantially the same as," is used to indicate that the only reduction in temperature stems from normally experienced loss due to the flow of material from one piece of equipment to another, or from conversion of sensible heat to latent heat by "flashing" where a pressure drop occurs.

The phrase, "hydrocarbons boiling within the gasoline boiling range," or "gasoline boiling range hydrocarbons," is intended to connote those hydrocarbons boiling up to a temperature in the range of 350° F. to about 450° F., including C₅-hydrocarbons, and, as is common in some localities, C₄-hydrocarbons. However, for the purpose of more clearly defining the component yields of the present process, "gasoline" will allude to a C₅-400° F. hydrocarbon fraction, notwithstanding that commercially-scaled units in various locales will raise or lower the end boiling point as dictated by the then current requirements.

Likewise, a "black oil" is intended to connote a hydrocarbonaceous mixture of which at least about 10.0% boils above a temperature of about 1050° F., and which has a gravity, ° API, of 25.0 or less. The greater proportion of such black oils contains 60.0% or more of material boiling above 1050° F., and in many instances, the material is considered totally "nondistillable." "Distillable hydrocarbons" are those normally liquid hydrocarbons, including pentanes, having boiling points below about 1150° F. Conversion conditions are intended to be those conditions imposed upon the first reaction zone in order to convert a substantial portion of the black oil to distillable hydrocarbons. The conversion conditions, within this first reaction zone, are intended to include temperatures above about 700° F., with an upper limit of about 800° F., measured at the inlet to the catalyst bed. Since the bulk of the reactions are exothermic, the temperature increases through the catalyst bed, and the reaction zone effluent will be at a higher temperature. In order that catalyst stability be preserved, it is preferred to control the inlet temperature such that the effluent temperature does not exceed about 900° F. Hydrogen is admixed with the first reaction zone charge stock, by means of compressive recycle, in an amount generally less than about 30,000 s.c.f./bbl., at the selected operating pressure, and preferably in an amount of from about 3000 to about 15,000 s.c.f./bbl., based upon fresh feed. The operating pressure will be greater than 1000 p.s.i.g., and generally in the range of about 1500 p.s.i.g. to about 3500 p.s.i.g. The reactor charge passes through the catalyst at a liquid hourly space velocity (defined as volumes of liquid hydrocarbon charge per hour, measured at 60° F., per volume of catalyst disposed in the reaction zone) of from about 0.25 to about 2.0, again being based upon fresh feed. When conducted as a continuous process, it is particularly preferred to introduce the mixture into the vessel in such a manner that the same passes through the vessel in downward flow. The internals of the reaction zone may be constructed in any suitable manner capable of providing the required intimate contact between the liquid charge stock, the gaseous mixture and the catalyst. In some instances it may be desirable to provide the reaction zone with a packed bed or beds of inert material such as particles of granite, porcelain, berl saddles, sand, aluminum or other metal turnings, etc., to facilitate distribution of the charge, or to employ perforated trays or special mechanical means for this purpose.

As hereinbefore set forth, hydrogen is employed in admixture with the charge stock, and preferably in an amount of from about 3000 to about 15,000 s.c.f./bbl. The hydrogen-containing gas stream, herein sometimes designated as "recycle hydrogen," since it is conveniently

recycled externally of the reaction zone, fulfills a number of various functions: it serves as a hydrogenating agent, a heat carrier, and particularly a means for stripping converted material from the catalytic composite, thereby creating still more available catalytically active sites for the incoming, unconverted hydrocarbon charge stock. There will be a net consumption of hydrogen; to supplement this, hydrogen is added to the system from any suitable external source.

The catalytic composite disposed within the first reaction zone can be characterized as comprising a metallic component having hydrogenation activity, which component is composited with a refractory inorganic oxide carrier material of either synthetic or natural origin. The precise composition and method of manufacturing the carrier material is not considered essential to the present process, although a siliceous carrier, such as 88.0% alumina and 12.0% silica, or 63.0% alumina and 37.0% silica, are generally preferred. Briefly, however, suitable metallic components having hydrogenation activity are those selected from the group consisting of the metals of Groups VI-B and VIII of the Periodic Table, as indicated in the Periodic Chart of the Elements, Fisher Scientific Company (1953). Thus, the catalytic composite may comprise one or more metallic components from the group of molybdenum, tungsten, chromium, iron, cobalt, nickel, platinum, palladium, iridium, osmium, rhodium, ruthenium, and mixtures thereof. The concentration of the catalytically active metallic component, or components, is primarily dependent upon the particular metal as well as the characteristics of the charge stock. For example, the metallic components of Group VI-B are preferably present in an amount within the range of about 1.0% to about 20.0% by weight, the iron-group metals in an amount within the range of about 0.2% to about 10.0% by weight, whereas the platinum-group metals are preferably present in an amount within the range of about 0.1% to about 5.0% by weight, all of which are calculated as if the components existed within the finished catalytic composite as the elemental metal.

The refractory inorganic oxide carrier material may comprise alumina, silica, zirconia, magnesia, titania, boria, strontia, hafnia, and mixtures of two or more including silica-alumina, alumina-silica-boron phosphate, silica-zirconia, silica-magnesia, silica-titania, alumina-zirconia, alumina-magnesia, alumina-titania, magnesia-zirconia, titania-zirconia, magnesia-titania, silica-alumina-zirconia, silica-alumina-magnesia, silica-alumina-titania, silica-magnesia-zirconia, silica-alumina-boria, etc. It is preferred to utilize a carrier material containing at least a portion of silica, and preferably a composite of alumina, silica and boron phosphate with alumina being in the greater proportion.

Similarly, the catalytic composites disposed within the second and third reaction zones will comprise metallic components from the metals of Groups VI-B and VIII of the Periodic Table, and compounds thereof, which components are composited with one or more of the refractory inorganic oxides previously set forth. However, since the catalytic composites in these two subsequent zones are intended to fulfill somewhat different functions, the second and third zones will, in most situations, make use of different catalysts. The applicability of the present process, particularly regarding the integration therein of the second and third reaction zones, may be illustrated by a two-stage process, the charge stock to which is the mixture of the first and second vapor phases as hereinbefore described. The function of the first reaction zone is essentially two-folds; it serves to concentrate a residuum fraction containing sulfur while simultaneously producing distillable hydrocarbons and converting sulfurous and nitrogenous compounds into ammonia, hydrogen sulfide and hydrocarbons. The quantity of sulfur remaining in the distillable fraction will, of course, be dependent upon the characteristics of the fresh black oil charge stock.

Whereas the second reaction zone has disposed therein

a catalytic composite having its principal activity directed towards nitrogen and sulfur removal, and inherently effects some hydrocracking of the heavier hydrocarbons, the catalyst in the third reaction zone is designed primarily to promote hydrocracking. The precise character, physical and chemical, of the third zone catalyst is dependent to a large extent upon the characteristics of the original black oil charge stock, the degree to which sulfurous and nitrogenous compounds have been converted in the first two zones, and whether intermediate removal of ammonia and hydrogen sulfide is intended.

Since the functions to be served within the second and third reaction zones are different, most applications of the present invention will involve different operating conditions and different catalysts, although not necessarily. Thus, the charge to the second reaction zone, in admixture with hydrogen in an amount of about 3,000 to about 15,000 s.c.f./bbl. of liquid hydrocarbon charge, is raised to a desired operating temperature within the range of about 500° F. to about 1000° F., prior to contacting the catalytic composite. The reactions are effected under an imposed pressure of about 100 pounds to about 3000 pounds per square inch, the hydrocarbon charge stock contacting the catalytic composite at a liquid hourly space velocity (defined as volumes of liquid charge per hour per volume of catalyst disposed within the reaction zone), within the range of from about 0.5 to about 10.0. In addition to the effective clean-up of the hydrocarbon charge stock, a significant degree of hydrocarbon conversion occurs whereby the heavier molecular weight hydrocarbons, boiling at a temperature of from about 700° F. to about 1050° F., and including the higher-boiling nitrogenous compounds, are converted, by highly selective cracking reactions into lower boiling hydrocarbons, from which the nitrogen is more readily removed. The conversion reactions are such that very little light, straight-chain paraffinic hydrocarbons are produced.

The catalyst disposed within the second reaction zone serves a dual function; that is, the catalyst is non-sensitive to the presence of both nitrogenous compounds and sulfurous compounds, while at the same time is capable of effecting the destructive removal thereof, and, as hereinabove set forth, the conversion of at least a portion of those hydrocarbons boiling at a temperature above about 700° F. A catalyst comprising comparatively large quantities of molybdenum, calculated as the element, composited with the carrier material of silica and from about 60.0% to about 78.0% by weight of alumina, is very efficient in carrying out the desired operation. A preferred catalytic composite, for utilization in this reaction zone, comprises from about 4.0% to about 45.0% by weight of molybdenum. In addition to minor amounts of nickel, from about 0.2% to about 10.0% by weight, like quantities of cobalt and/or iron may be employed in combination with the relatively large amounts of molybdenum.

As hereinbefore stated, there may or may not be separation facilities between the second and third reaction zones, for the purpose of removing ammonia and hydrogen sulfide from the second reaction zone product effluent. The preferred scheme, from the viewpoint both of economics and ease of operation, is to introduce the total effluent into the third reaction zone without intervening separation. The obvious advantage is the elimination of additional separation equipment between the two involved reaction zones. Such a series-type flow also requires one less compressor for hydrogen circulation since the hydrogen may be recycled from the effluent of the third zone to the charge to the second zone. Furthermore, the cost of utilities attributable to heating is significantly reduced since there is no intentional condensation or cooling of the second zone effluent aside from that resulting via radiation loss. The particular scheme selected is, of course, dependent upon a number of variables including eco-

nomic considerations and the precise character or the catalytic composite disposed within the third reaction zone.

At least a portion of the effluent from the second reaction zone is introduced into the third reaction zone at a temperature within the range of about 500° F. to about 950° F. Due to the characteristics of the charge stock to the third reaction zone, the operating conditions within the same are relatively mild. The third reaction zone is maintained under an imposed pressure within the range of about 100 to about 3000 p.s.i.g., and preferably from about 1000 p.s.i.g. to about 2500 p.s.i.g. The rate of hydrocarbon charge will be within the range of from about 0.25 to about 5.0 liquid hourly space velocity. Catalytic composites which comprise at least one metallic component selected from Groups VI-B and VIII of the Periodic Table, and a composite of silica and from about 12.0% to about 30.0% by weight of alumina, constitute suitable hydrocracking catalysts for use in the conversion of the nitrogenous compound-free charge stock into lower boiling hydrocarbon products. The total quantity of catalytically active metallic components is within the range of from 0.1% to about 20.0% by weight of the total catalyst. The Group VI-B metal, such as chromium, molybdenum, or tungsten, is usually present within the range of from about 0.5% to about 10.0% by weight of the catalyst. The Group VIII metals, which may be divided into two sub-groups, are present in an amount of from 0.1% to about 10.0% by weight of the total catalyst. When an iron subgroup metal such as iron, cobalt, or nickel, is employed, it is present in an amount of from about 0.2% to about 10.0% by weight, while, if a noble metal such as platinum, palladium, iridium, etc., is employed, it is present within an amount within the range of from about 0.1% to about 5.0% by weight of the total catalyst. Suitable catalysts, for utilization within the hydrocracking reaction zone, include, but are not limited to the following: 6.0% by weight of nickel and 0.2% by weight of molybdenum; 6.0% by weight of nickel; 0.4% by weight of palladium; 6.0% by weight of nickel and 0.2% by weight of palladium; 6.0% by weight of nickel and 0.2% by weight of platinum; etc. Where appropriate, these metallic components may be impregnated, or ion-exchanged, upon a crystalline aluminosilicate molecular sieve, a variety of which are commonly referred to in the art by the broad term "zeolites." For example, one such catalyst, which exhibits the desired characteristics of stability and activity, is a composite of 5.3% by weight of nickel and a synthetically prepared faujasite distributed throughout a silica matrix. The total effluent from the third reaction zone is introduced into a high-pressure, low-temperature—i.e., 60° F. to about 140° F.—receiver from which a hydrogen-rich gaseous phase is withdrawn and recycled. The normally liquid hydrocarbon phase, containing some light paraffins and butanes, is admixed with the fresh black oil charge stock for separation as hereinbefore set forth.

Other conditions and preferred operating techniques will be given in conjunction with the following description of the present process. In further describing this process, reference will be made to the accompanying figure which illustrates a specific embodiment. In the drawing, the embodiment is presented by means of a simplified flow diagram in which such details as pumps, instrumentation and controls, heat-exchange and heat-recovery circuits, valving, start-up lines and similar hardware have been omitted as being non-essential to an understanding of the techniques involved. The use of such miscellaneous appurtenances, to modify the process, are well within the purview of one skilled in the art.

DESCRIPTION OF DRAWING

For the purpose of demonstrating the illustrated embodiment, the drawing will be described in connection with the conversion of a whole crude black oil charge stock in a commercially scaled unit. It is to be understood that the charge stock, stream compositions, operating con-

ditions, design of fractionators, separators and the like, are exemplary only, and may be varied widely without departure from the spirit of my invention, the scope of which is defined by the appended claims. With reference now to the drawing, the charge stock, having the properties set forth in Table I, is introduced into the process via line 1:

Table I.—Charge stock properties

Gravity, ° API at 60° F.	23.9
Sulfur, wt. percent	2.1
Nitrogen, p.p.m.	1,950
Conradson carbon residue, wt. percent	6.7
Total metals, p.p.m.	36
Heptane-insolubles, wt. percent	1.0

An ASTM distillation of the black oil indicates that about 11.5% by volume has a 400° F. end point, 19.4% is middle-distillate boiling from 400° F. to 650° F. and 69.1% boils above 650° F. The 50.0% distillation temperature is about 905° F., and 35.0% boils above a temperature of 1030° F. The unit is designed to process 2,000 bbl./day of fresh charge stock, and it is intended to maximize the ultimate yield of 400° F. end point gasoline, including butanes for their blending value.

The charge in line 1 is admixed with the normally liquid portion of a hydrocracked product effluent in line 34. The mixture continues through line 1 into product separation zone 2. Although indicated as a single vessel for the purpose of simplifying the illustration, product separation zone 2 may take the form of multiple fractionations and/or distillations designed to facilitate the recovery of one or more components or streams in a substantially pure state. In any event, product separation is conducted at conditions of pressure and temperature such that a heavy fraction containing asphaltenes and boiling above 400° F. is removed via line 3. The initial boiling point of this heavy fraction is obviously dependent upon the desired end point of the ultimate gasoline product.

The heavy fraction continues through line 3 into one side of a subatmospheric, sectioned flash zone 4 which is maintained at a pressure of about 50-60 mm. of Hg absolute. Hot flash zone 4 is sectioned in the lower portion thereof by means of imperforate plate 5 which provides individual flash zones into one of which the heavy fraction in line 3 is introduced. As hereinafter set forth, a portion of the first reaction zone product is introduced into the second side of flash zone 4 by way of line 14. A residuum fraction in an amount of about 142 bbl./day and having an ° API gravity of 2.0, is removed via line 41. It should be noted that the residuum fraction, which contains the unconverted high molecular weight asphalts, is withdrawn from that side of hot flash zone 4 into which the reaction zone effluent is introduced. A synthetic crude stream, containing the native or straight-run asphaltenes is removed via line 6 from that side of the hot flash zone into which the heavy fraction was introduced via line 3. It should further be noted that imperforate plate 5 extends only through a lower portion of flash zone 4, so that the upper portion of the latter, which may be suitably equipped with side-to-side pans, is shared in common as distillation means by the two lower sections formed by imperforate plate 5. The use of sectioned flash zone 4 in the foregoing manner stems from recognition of the fact that the character of native asphaltenes (or straight-run asphalts) is significantly different from those residual asphalts which have been subjected to reaction conditions, but remain unconverted to soluble hydrocarbons. Basically, the former are characterized by a hydrogen/carbon atomic ratio of about 1.0, although in some instances the ratio can be higher, whereas the residual asphalts have a hydrogen/carbon atomic ratio less than 1.0, and often as low as 0.75. For example, analyses have indicated that the native asphalts in a crude tower bot-

tom product comprise 84.15% carbon and 7.23% hydrogen, and have a hydrogen/carbon atomic ratio of 1:02. The residual asphalts, following an initial treatment of this stock, contained 91.16% carbon and 5.93% hydrogen, and indicated a hydrogen/carbon atomic ratio of 0:77. The principal function, therefore, of the sectional hot flash zone is to provide a charge to the first reaction zone which is highly concentrated in the straight-run asphalts compared to the residual cracked asphalts. Stream 6 will be more concentrated in the straight-run asphalts after being admixed with a portion of the first reaction zone effluent in line 13, thereby forming the liquid charge to the first reaction zone. The sectioned flash zone also avoids the necessity of installing a second such zone for the purpose of concentrating the residual asphalts in line 14.

The amount of liquid phase from hot separator 12, which continues through line 13 to be admixed with the synthetic crude in line 6, is such that the combined feed ratio is about 2.0. The liquid mixture is combined with 10,000 s.c.f./bbl. of hydrogen from line 7, based upon the synthetic crude only, and, following suitable heat exchange with various effluent streams not illustrated, continuous through line 6, into heater 8 wherein the temperature is increased to a level such that the reactor 10 inlet temperature is about 725° F. The heated mixture leaves heater 8 via line 9, and enters first reaction zone 10 at a LHSV of 0.5, based upon the synthetic crude only. Reaction zone 10 is maintained under an imposed pressure of about 3,000 p.s.i.g. The reaction product effluent, at a temperature of about 825° F., is withdrawn via line 11, and is passed thereby into hot separation zone 12 at a pressure somewhat less than 3,000 p.s.i.g., the drop in pressure being due solely to fluid flow through the system. After its use as a heat-exchange medium, the effluent is introduced into zone 12 at a temperature of 750° F. A principally vapor phase is withdrawn from the hot separator 12 through line 15, and a principally liquid phase is withdrawn via line 13. A portion of this liquid phase, in this instance 756 bbl./day, continues via line 13 to combine with the synthetic crude in line 6. The remaining portion is diverted through line 14 into a hot flash zone 4. The greater proportion of the vapor phase in line 15 consists of hydrocarbonaceous material boiling below about 700° F., while the liquid phase in line 13 is principally 700° F.-plus hydrocarbonaceous material.

In the illustrated embodiment, the material in line 14 enters the hot flash zone 4 at a temperature of about 730° F., the zone being at a subatmospheric pressure of about 50 mm. of Hg absolute. A residuum fraction, having an average molecular weight above 850, and a gravity of 2.0 ° API, is removed via line 41 in an amount of about 9.2 wt. percent of the fresh hydrocarbon charge (about 8.0% by volume). A second principally vapor phase is removed through line 35. The vapor phase in line 15 is introduced into cold separator 16 which is at a temperature of about 80° F. Cold separator 16 serves as the pressure control point of the first reaction zone, the control maintaining a pressure of about 3,000 p.s.i.g. on reactor 10. A principally vapor phase is withdrawn from cold separator 16 through line 17 by means of compressor 19. This hydrogen-rich stream is recycled via line 7 to combine with the normally liquid charge in line 6. Makeup hydrogen, to compensate for that consumed in reactor 10 as well as subsequent reaction zones, is introduced from any suitable external source via line 18. Although indicated as entering the process upstream of compressor 19, it is understood that the same may enter the process flow at any suitable point as may be dictated by various engineering considerations. A component analysis of the effluent from reactor 10 (exclusive of any recycled material) is presented in the following Table II, which reflects a hydrogen consumption of 0.7% by weight of the fresh charge in line 1.

Table II.—Analysis, reactor 10 effluent

Component:	Wt. percent ¹
Ammonia	0.07

650° F.-1050° F.	21.03
Residuum	9.15

¹ Weight percent of fresh charge in line 1.

With reference once again to the drawing, a third liquid phase is withdrawn from cold separator 16 via line 20, is combined with the second vapor phase from flash zone 4, line 35, and a hydrogen-rich recycle gas phase in line 22, the mixture continuing through line 20 into heater 21. After the temperature has been raised to about 650° F., the mixture passes through line 25 into a second catalytic reaction zone 26. The normally liquid feed to reactor 26 is about 2667 bbl./day at a combined feed ratio of about 1.6, and contacts the catalytic composite at a liquid hourly space velocity of about 1.05 (exclusive of recycle material). The pressure maintained on reactor 26 is somewhat higher than 1750 p.s.i.g. The reactor effluent is withdrawn via line 27, and, where necessary, passes into heater 28. Component analyses of reactor 26 effluent, exclusive of recycled material, are presented in the following Table III, and reflects a hydrogen consumption therein of 1.22% by weight of the fresh charge stock in line 1.

Table III.—Analysis, reactor 26 effluent

400° F.-650° F.	72.45
Residuum	

¹ Weight percent of fresh charge in line 1.

These data indicate that the remainder of the sulfurous and nitrogenous compounds have been converted, and that a significant quantity of lower boiling hydrocarbons have been produced.

In many instances, the effluent from reactor 26 will be at a higher temperature in line 27 than is desired at the inlet to reactor 30. In such a situation, it is conceivable that heater 28 could be eliminated. However, since common practice dictates utilizing reactor 26 effluent as a heat-exchange medium, whereby its temperature is lowered, at least some heat will be required to raise the temperature. This is accomplished by way of heater 28, which will have an extremely low heater duty in any case; the heated stream passing via line 29 into reactor 30 at a temperature of about 700° F. The analysis of the reactor 30 effluent in line 31 is presented in the following Table IV. A hydrogen consumption of 1.29% by weight, of the fresh charge stock in line 1, is reflected in the Table.

Table IV.—Analysis, reactor 30 effluent

Residuum	

¹ Weight percent of fresh charge stock in line 1.

The figures presented do not include about 1,000 bbl./day of 400° F.-plus hydrocarbon recycle as hereinafter described.

Reactor 30 product effluent is condensed and passed into cold separator 32, via line 31, at a temperature of about 80° F. A hydrogen-rich gaseous phase is withdrawn therefrom via line 33, and is recycled by way of compressor 24, through line 22, to combine with the charge to reactor 26 in line 20. To compensate for the 2.51% by weight of hydrogen consumed in reactors 26 and 30, makeup hydrogen is diverted from line 18 through line 23 into line 22. A fourth liquid phase hydrocracked effluent passes through line 34, is combined with the fresh black oil charge in line 1, and the mixture introduced into product separation zone 2.

Product separation is effected to segregate a light hydrocarbon stream in line 36, a butane-rich stream in line 37, a pentane-hexane stream in line 38 and a C₇-400° F. gasoline fraction in line 39. The 400° F.-plus material, including native asphaltenes, is removed via line 3, and is passed into hot flash zone 4 as previously described. In one embodiment of my invention, finding primary utility in the processing of heavier black oils, a middle-distillate, 400° F.-650° F. fraction is withdrawn from product separation zone 2 via line 40, to be introduced into reactor 26 by way of lines 35 and 20. An added advantage, notwithstanding a somewhat higher product separation cost, resides in a significantly reduced hot flash zone which costs more dollars/barrel of capacity than fractionation facilities. Obviously, it is within the scope of my invention to divert a portion of the middle-distillate in line 40 into line 3 for introduction into flash zone 4.

To summarize the results, the overall product distribution is presented in the following Table V:

TABLE V.—OVERALL PRODUCT DISTRIBUTION

Component	Wt. percent	Vol. percent
Hydrogen	(3.21)	
Ammonia	0.19	
Hydrogen sulfide	2.23	
Methane	0.59	
Ethane	0.79	
Propane	3.16	
Butanes	11.15	18.20
Pentanes	8.13	12.08
Hexanes	11.24	14.94
C ₇ -400° F.	56.58	68.81
400° F.-650° F.		
650° F.-1,050° F.		
Residuum	9.15	8.03

A summary in terms of bbl./day of the major streams in the foregoing described process is herein presented for further clarification and description of the illustrated embodiment. On the basis of a fresh charge stock rate of 2,000 bbl./day in line 1: 230 bbl./day is 400° F. end point straight run gasoline, which is recovered in line 39, along with 1218 bbl./day of "product" gasoline; 1770 bbl./day constitute the 400° F. reduced crude, which is withdrawn in line 3 in combination with about 1,000 bbl./day of a 400° F.-plus recycle; the residuum fraction is 142 bbl./day; the charge to reactor 10 in line

6 is 1512 bbl./day, of which 756 bbl./day is recycle from hot separator 12; the effluent from reactor 10 is 1551 bbl./day, and the charge to reactor 26 is 2667 bbl./day; the effluent from reactor 26 is 3018 bbl./day, and the total charge to product separation is 5018 bbl./day; and, the butane concentrate is in an amount of 322 bbl./day, while the pentane-hexane fraction is recovered in an amount of 478 bbl./day.

Of further interest is the fact that the residuum fraction contains 2.07% by weight of sulfur which, when considered in conjunction with the 2.23% by weight of hydrogen sulfide, indicates that the product streams are substantially sulfur-free, and, therefore, are well-suited for further processing. Also, the butane stream is 70.0% iso-butane while the pentanes in the pentane-hexane concentrate are 93.0% isopentane. This further enhances the value of these products.

The foregoing specification and examples indicate the method by which the present process is effected, and illustrate some of the benefits afforded through the utilization thereof. The present process has been shown to be a valuable tool to petroleum refining in its ability to convert black oils into more valuable distillable hydrocarbon products.

I claim as my invention:

1. A process for the conversion of an asphaltene-containing, sulfurous hydrocarbon charge stock into lower-boiling hydrocarbon products which comprises the steps of:

- (a) admixing said charge stock with a principally liquid hydrocracked product effluent and separating the resulting mixture to provide an asphaltene-containing heavy fraction having an initial boiling point above about 350° F.;
- (b) introducing said fraction into one side of a sub-atmospheric sectioned flash chamber and withdrawing a first liquid phase from said side;
- (c) reacting said first liquid phase with hydrogen at a temperature above about 700° F. and at a pressure greater than about 1000 p.s.i.g. in a first catalytic reaction zone, and separating the resulting reaction zone effluent in a first separation zone, at substantially the same pressure and at a temperature above about 700° F., to provide a second liquid phase and a first vapor phase;
- (d) introducing at least a portion of said second liquid phase into a second side of said subatmospheric sectioned flash chamber, removing an asphaltene-containing residuum fraction from said second side and a second vapor phase from an upper, nonsectioned portion of said flash chamber;
- (e) separating said first vapor phase in a second separation zone, at a temperature of from 60° F. to about 140° F. and a pressure substantially the same as said

first separation zone, to provide a third liquid phase and a hydrogen-rich third vapor phase, and recycling at least a portion of the latter to combine with said first liquid phase;

- (f) combining said third liquid phase with said second vapor phase and reacting the resulting mixture with hydrogen in a second catalytic reaction zone at conditions selected to convert sulfurous and nitrogenous compounds into hydrogen sulfide, ammonia and hydrocarbon, and to produce lower molecular weight hydrocarbons;
- (g) reacting at least a portion of the resulting second reaction zone effluent in a third catalytic reaction zone at hydrocracking conditions and in contact with a hydrocracking catalytic composite;
- (h) separating the resulting third reaction zone effluent, at a temperature of from about 60° F. to about 140° F., in a third separation zone to provide a hydrogen-rich fourth vapor phase and a fourth normally liquid hydrocarbon phase; and,
- (i) combining said fourth liquid phase with said charge stock and separating the resulting mixture as aforesaid.

2. The process of claim 1 further characterized in that said second liquid phase is combined with said first liquid phase in an amount to produce a combined feed ratio to said first reaction zone of from about 1.5 to about 3.5.

3. The process of claim 1 further characterized in that the temperature of the first reaction zone effluent, introduced into said first separation zone, is within the range of from about 700° F. to about 760° F.

4. The process of claim 1 further characterized in that said hydrogen-rich fourth vapor phase is recycled to combine with said third liquid phase and said second vapor phase.

5. The process of claim 1 further characterized in that said mixture of charge stock and fourth liquid phase is separated to provide a middle-distillate fraction, and combining said middle-distillate fraction with said second vapor phase and said third liquid phase.

6. The process of claim 1 further characterized in that the total second reaction zone effluent is introduced into said third catalytic reaction zone.
